WATCHCASE BEZEL

Harry Dinhofer, New York, N. Y.

Application October 21, 1949, Serial No. 5,638

Term of patent 7 years

(Cl. D42—8)

To all whom it may concern:

Be it known that I, Harry Dinhofer, a citizen of the United States of America, and resident of the city, county, and State of New York, have invented a new, original, and ornamental Design for a Watchcase Bezel, of which the following is a specification, reference being had to the accompanying drawing, forming part thereof in which:

Fig. 1 is a top plan view of a watchcase bezel showing my new design.

Fig. 2 is a side elevational view of the same, and Fig. 3 is an end view of the same.

I claim:

The ornamental design for a watchcase bezel, substantially as shown.

HARRY DINHOFER.
